HAIR DRIER

Albert G. Thomas, Alexandria, Va.

Application March 7, 1945, Serial No. 581,363

5 Claims. (CL. 34—99)

1

This invention relates to beauty shop equipment and particularly to hair driers which are widely used for conditioning the hair of patrons following shampooing, oil treatments, permanent waves, etc. The present invention embodies several distinct improvements and advantages over contemporary apparatus for such purpose.

One of the objects of my invention is to provide a hair drier operable through adjustable hot and cold air cycles, thus avoiding excessive heating of the scalp and resulting from continuous heat application and variable to suit the requirements of the individual.

Another object of my invention is to provide a hair drier having a dual air pressure and air suction circulating system.

Another object is to provide a hair drier having sound deadening means in the air passage to the helmet, for lessening fatigue.

An additional object of this invention is to provide a hair drier of increased efficiency by reason of the proximity of the air inlets to corresponding air outlets, thus providing a "local" drying at a number of individual areas.

Other objects and advantages of this invention will be apparent from the following description and taken in connection with the drawings in which:

Figure 1 is a vertical sectional view of one form of my invention;

Figure 2 is a vertical part sectional view of a hair drier generally similar to that shown in Figure 1 but having the inlet and exhaust fans mounted on the same shaft and driven by a common motor.

Referring now to the drawings and first, to Figure 1, a frame generally indicated at 1 includes a lower housing 2, a hollow, upright conduit 3 and a pair of hollow upper arms 4 and 5 serving as inlet and exhaust passages respectively for the drier helmet generally indicated at 6. An electric motor 7 suitably mounted in housing 2 rotates fan 8 to draw air in through apertures 9 and 10 of the housing, thence through ports 11 and 12 in a horizontal wall 13 and drives the same through a transverse layer of porous, sound-insulating material 14 into the hollow conduit 3. This material may consist of loose asbestos, rock wool, shredded wood, or the sound filter may consist of baffles. Worm 7a is fastened coaxially to the shaft of motor 7 and drives gear 16a having projecting face pin 16 and which gear is supported for rotation by coaxial bearing pin 16b fastened to support 15. Pin 16

operates in slot 17 of a lever 18 pivoted at 19 to support 15 and moves valves 20, 21 alternately up and down to open and close ports 11 and 12, respectively. Heating element 22 is positioned 5 in a lower compartment defined by the wall of housing 2 and an inner preferably heat-insulating wall 2a and is electrically energized through connections as shown. Thus, alternate charges 10 of warm and relatively cool air will be forced into the inlet arm 4 and helmet 6. This tends to prevent overheating of the subject. A motor and fan assembly 23 is suitably mounted in the lower portion of upper arm 5 and draws air through the porous sound insulator or baffle 24 and then forces it to the outside through opening 25. Insulator or baffle 24 contributes to 15 the external as well as internal quiet operation of the drier unit while exhaust fan 23 increases the circulation with little increase in operating 20 cost. The sound filters 14 and 24 also reduce sound resonance effects.

Helmet or head piece 6, it will be observed, is comprised of a dome-shaped outer wall 26 in communication with inlet arm 4 and forms with 25 a similarly shaped inner wall 27 a circulating inlet space 28. Wall 27 is formed of rigid material such as metal or plastic, but may be of soft material such as cork or rubber. Its inner surface is formed with inwardly projecting truncated cones 29 which are apertured to communicate with space 28. Upper arm 5 also communicates with the interior of the wall 27 to draw the air therefrom. Suitable air sealing means such as a rubber ring may be used inside wall 27 30 and surrounding the head of the patron if desired. It will be observed that the conical projections 29 serve to space the helmet from the head of the wearer and by reason of the inflow of air at these points a "floating" and not at all 35 uncomfortable support for the head will be provided. In fact the device may be inclined so that the subject's head will rest upon the supports 29, being partially lifted by the incoming air. The depressed portions 29a allow the air 40 to be withdrawn through the hair and out hollow arm 5 from which it is carried through passage 45 25 by fan 23.

Valves 20 and 21 are preferably pivotally mounted on lever 18 as shown and are movable 50 against springs 20a and 21a which insure that the valves will close openings 11 and 12 without excessively accurate adjustments. Electrical connections are made through plug 7a.

Valves 20 and 21 can be threaded upon their 55 respective pivoted rod supports so that they can

be adjusted in position to vary the length of cycles of warm air and cool air for different subjects or different conditions. Various other means for accomplishing this will be readily apparent.

In Figure 2 there is shown a form of the invention similar to Figure 1 but utilizing an exhaust fan 23a which is mounted on the same shaft as the blower fan 8a, and a slightly modified form of helmet. In this embodiment air enters apertures 10a and 10b in outer and inner walls 2a and 2b respectively, of the lower housing and across a heating coil 22a and through a valve port similarly arranged to that shown in Figure 1. Air entering the apertures on the opposite side of the housing is not heated, due to the wall 2c, but is drawn upward through the corresponding valve port by the fan 8a. The latter moves the air upward through the annular conduit 3a and into the space 28b, and through apertures 33c in the rigid helmet wall 27d and apertures 33d in the semi-rigid inner wall 30a. Exhaust of the air is effected through the inner conduit 5c which extend sthrough the inner wall 30a and passes outside through pipe 9a. Rods 8d may connect outer pipe or casing 2b and inner pipe 5c. This form of the invention provides a convenient, symmetrical design.

It is to be understood that the above preferred forms of my invention are merely illustrative of the principles which have been disclosed herein. Therefore, I desire the same to be limited only by the subjoined claims.

I claim:

1. In a hair drier, a headpiece, a blower for moving air to said headpiece, a motor to drive said blower, a duct to direct air from said blower to said headpiece, partition means having an opening therein for heated air and an opening therein for relatively cool air on the intake side of said blower, means for heating air in a chamber formed by said partition means and connected with said heated air opening, a pair of valves for periodically closing said openings, and means driven by said motor for actuating said valves for alternately distributing to said headpiece heated air and relatively cool air.

2. In a hair drier, a headpiece, a blower for moving air to said headpiece, a motor to drive said blower, a duct to direct air from said blower to said headpiece, partition means having an opening therein for heated air and an opening therein for relatively cool air on the intake side of said blower, means for heating air in a chamber formed by said partition means and connected with said heated air opening, a pair of valves for periodically closing said openings, and means driven by said motor for actuating said valves for alternately distributing to said headpiece heated air and relatively cool air, said valve-actuating means including means for adjusting said valves to vary the ratio of heated air to relatively cool air supplied to said duct.

3. In a hair drier, a headpiece, a first blower to move air to said headpiece, a duct to direct air from said first blower to said headpiece, a second blower to move air away from said headpiece, another duct to direct air from said headpiece to said second blower, means for driving said blowers, partition means on the intake side of said first blower forming a chamber for heated air and a chamber for relatively cool air and hav-

ing an opening therein connecting with said heated air chamber and an opening therein connecting with said relatively cool air chamber, a pair of valves for periodically and alternately closing said openings, means in said heated air chamber for heating air, and means driven by at least a part of said blower-driving means for actuating said valves to distribute to said first blower alternately said heated air and said relatively cool air.

4. In a hair drying device, a headpiece, a blower for moving air to said headpiece, a duct to direct air from said blower to said headpiece, a motor to drive said blower, casing means for said blower having port means therein for flow of heated air therethrough and having other port means therein for flow of relatively cool air therethrough, a valve for periodically reducing flow of said heated air through its port means, another valve for periodically reducing flow of said relatively cool air through its port means, means for heating air to pass through said first named port means, said device including a pivoted member to support said valves, and means associating said motor with said pivoted member to cause rocking thereof to cause said valves to admit alternately to said blower heated air and relatively cool air.

5. In a hair drying device, a headpiece, a blower for moving air to said headpiece, a duct to direct air from said blower to said headpiece, a motor to drive said blower, casing means for said blower having port means therein for flow of heated air therethrough and having other port means therein for flow of relatively cool air therethrough, a valve for periodically reducing flow of said heated air through its port means, another valve for periodically reducing flow of said relatively cool air through its port means, means for heating air to pass through said first named port means, and means associating said motor with said valves to actuate said valves to cause distribution to said blower alternately heated air and relatively cool air.
